CLAIM

The ornamental design for a hand-graspable grip, as shown and described.

DESCRIPTION

FIG. 1 is a rear view of a hand-graspable grip;
FIG. 2 is a bottom perspective view thereof;
FIG. 3 is a bottom view thereof;
FIG. 4 is a front view thereof;
FIG. 5 is a first side perspective view thereof;
FIG. 6 is a second side perspective view thereof;
FIG. 7 is a top view of a hand-graspable grip;
FIG. 8 is an upper perspective view thereof;
FIG. 9 is an upper front perspective view thereof; and,
FIG. 10 is a lower front perspective view thereof.
The broken lines illustrate portions of the hand graspable grip that form no part of the claimed design.
